UNITED STATES PATENT OFFICE.

NATHANIEL D. HULL, OF FORT WAYNE, INDIANA.

LIQUID-DISPENSING DEVICE.

1,176,757.

Specification of Letters Patent. Patented Mar. 28, 1916.

Application filed February 13, 1914, Serial No. 818,451. Renewed September 9, 1915. Serial No. 49,824.

To all whom it may concern:

Be it known that I, NATHANIEL D. HULL, a citizen of the United States, residing at Fort Wayne, in the county of Allen and State of Indiana, have invented new and useful Improvements in Liquid-Dispensing Devices, of which the following is a specification.

This invention relates to devices for dispensing liquids wherein by the deposit of a coin the operating mechanism is released and a measured quantity of liquid is discharged from a storage tank.

The device is particularly adapted for use as a dispensing device for liquid fuels, such as gasolene where the storage tank is buried in the ground and the dispensing apparatus is on top of the ground or in a building, thereby eliminating the element of fire hazard.

Among the many objects of my invention are to provide a simple and efficient device by which a measured quantity of liquid may be obtained according to the size of the coin deposited in the device; the provision of means for indicating the quantity of fuel in the storage tank and for automatically locking the device from operation when the tank is empty; the provision of a novel form of pump and actuating mechanism; novel means for automatically cutting off the delivery of the fuel when the amount supplied is that which the coin which has been deposited will purchase, and novel means for releasing the locking mechanism upon the deposit of a coin, the device needing no attendant and being installed on a street or highway where it is accessible to users of the fuel at any and all times. I accomplish these objects, among others hereinafter recited, by the novel combination, construction and arrangement of parts hereinafter set forth, one embodiment of which I have illustrated in the accompanying drawings, in which—

Figure 1 is a side elevation of the dispensing apparatus, the housing being in section; Fig. 2, a plan view of the same, the top of the housing being in section; Fig. 3, a detail in plan view of the main plungers by which the pump mechanism is connected to the operating devices and the measuring devices are controlled; Fig. 4, a longitudinal section of one of the main plungers; Fig. 5, a vertical cross section on line 5—5 of Fig. 1 the unlocking plungers and coin tubes being omitted; Fig. 6, a front elevation of the hose drum; Fig. 7, a vertical central cross section of the same; Fig. 8, an elevation in section of the lower part of the housing showing the filter, said view being a continuation of Fig. 5; Fig. 9, a front view of the pump mechanism housing with the storage tank and devices for indicating the quantity of liquid in the tank and for closing the coin apertures; Fig. 10, a front view of the complete device excluding the storage tank and Fig. 11, a side view of the same.

Referring to the drawings, 1 is the top cap, 2 the upper part and 3, the lower part of the housing in which the operating mechanism is mounted, parts 2 and 3 being secured together by bolts 8, the top being suitably secured to housing 2. Suitably mounted in bearings formed in the two side walls of housing 2 is a revoluble shaft 5 which projects through one wall and is provided at its projecting end with a crank 63, collars 64 and 65, removably secured to the shaft, preventing longitudinal movement of the shaft. Secured to this shaft are a suitable number of cams 7 and a circular rack 6. A pawl 9 pivotally mounted on a boss which is carried by housing 2, is adapted to engage rack 6. Pawl 9 carries a fixed latch 9^a which is adapted to engage a pawl 117 suitably mounted on bracket 40, which is carried by housing 2. (Figs. 1 and 2.) A spring 29 is connected to pawl 117 and to the housing 2 which opposes the movement of the pawl. In bearings 11 is supported a revoluble shaft 66 on the lower end of which is a gear 10 which is in mesh with a gear 62 secured to shaft 5. At the upper end of shaft 66 is a gear 12 which is in mesh with gear 13 loosely mounted on horizontal shaft 18, said shaft being carried by bearings 17 and 19 provided in bracket 17^a which projects from frame 11^a. The opposite side of gear 13 forms one jaw 13^a of a clutch which is adapted to be engaged by the other clutch jaw 14 suitably secured to shaft 18, a spring 116 between the two jaws of the clutch opposing the connecting movement of the same. The opposite end of the jaw 14 is provided with a gear 15 adapted to be brought into mesh with gear 16 which is secured to shaft 16^a. Shaft 16^a is borne by bracket 21, and drum 20 is also secured to shaft 16^a, upon which drum a cable 22 is adapted to be wound as the drum is rotated by gear 16 as hereafter described.

Jaw 14 is grooved peripherally and the groove is engaged by two pins 23 fixed in the ends of yoke 55 (Fig. 1), the yoke being secured on shaft 61 revolubly supported by housing 2. Secured to shaft 61 and projecting downwardly therefrom are three levers 56 which are adapted to be rocked by three fingers 57 which project upwardly from three main plungers 30. The rocking of the levers rotates shaft 61 and, by means of yoke 55, which moves with the shaft, the jaws of the clutch are forced together to connect gear 13 to shaft 18 and gear 15 to gear 16 whereby cable drum 20 is rotated and the pump is operated as hereafter described.

On the opposite end of shaft 18 is secured a crank disk or wheel 24 to which is suitably connected the upper end of connecting rod 33, the lower end of the rod being connected by crosshead and pin 44 to the upper end of plunger rod 48, which rod passes entirely through both top and bottom heads 47 of cylinder 46, suitable stuffing boxes 45 being provided in the heads. A suitable piston or plunger is secured to rod 48 and within cylinder 46 which is reciprocated between the cylinder heads when crank disk 24 revolves upon the clutch jaws being connected as above described. The pump is double acting, suction pipe 38 being connected to the cylinder adjacent both heads thereof and discharge pipe 49 being similarly connected to the cylinder. Suitable check valves 39 are provided in the connections between suction pipe 38 and the cylinder and suitable check valves 72 are provided in the connections between discharge pipe 49 and the cylinder. All the check valves are entirely outside the cylinder.

Suction pipe 38 leads to a filter 84 which is arranged within housing 3, and which will be described hereinafter. A pipe 92 connects the filter to a valve 105, branch 106 of the valve being connected to pipe 112 which passes through an opening in the tank and may be provided at its lower end with a suitable valve 113. A bushing 107 and flange 110, through which pipe 112 passes, prevent the escape of gases from the tank.

Discharge pipe 49 is connected at its upper end to drum 50, by which pipe the drum is supported, a lug 2^a on housing 2 (Fig. 7) serving as a pivot. Within the drum is an L shaped pipe or tube 76 having an L at its outer end to which hose 51 is connected by a suitable coupling. The central horizontal arm of the tube 76 is secured to the web of the drum and passes through a hub 79^a formed on the web, a sufficient space being provided between the hub and tube to admit of packing 79. The end of said arm is fitted into a collar 78^a provided on the

end of pipe 78 which pipe is secured to an elbow in the upper end of pipe 49. The outer end of hub 79^a is threaded and packing nut 77 is engaged on said threaded end of the hub and serves to force collar 78^a 70 on pipe 78 against packing 79 and render the joint between pipes 76 and 78 tight.

A suitable spring 75 is secured at one end to lug 80 on housing 2 and is coiled about the hub the opposite end of the spring being bent and passing through the case of the drum to abut pipe 76. This spring, when the drum has been rotated while unwinding the hose, is of sufficient strength to rotate the drum in the opposite direction and rewind the hose. The hose at its forward end, is passed through an opening in partition 59^a and is provided at said end with a nozzle 58. A sleeve 59 encircles the hose 50 and projects through the partition 59^a, a 85 collar 59^b on the opposite side of wall 59^a being secured to the sleeve. A spring 60 encircles the sleeve and bears at one end on wall 59^a and at its other end on a flange 59^c secured to the sleeve. The sleeve prevents 90 the nozzle from passing too far into the space A and the spring prevents injury to the hose and jar to the several parts when the drum winds up the hose. A beveled lug 50^a is provided on the inner periphery of the 95 drum 50 and a pin 120 movably mounted on spindle 121 carried by bracket 34 which is mounted on bearing 11, is in contact with said inner surface of the drum and when the hose is wound up the pin bears against 100 the vertical wall of the lug, thereby preventing the withdrawal of the hose. A rod 25, secured to the pin 120, extends forwardly and is connected to a lever 27^a (Fig. 1) secured to a collar 27 which is mounted on 105 shaft 118, which shaft is mounted on housing 2. Another lever 27^b is also secured to collar 27 and is connected by rod 27^c to pawl 9 (Fig. 1). Levers 27^d are secured to shaft 118 and their lower ends are so positioned relatively to the plungers 26 that when a coin is dropped into one of the plungers and said plunger is drawn forwardly by grasping knob 4 on said plunger the coin will strike the lever above that 115 plunger and force it forwardly, thereby causing shaft 118 to rotate and elevate levers 27^a and 27^b by which the hose, drum and main shaft 5 are unlocked and both may be freely rotated.

The three plungers 26 are U shaped and are slidable in a casing 40. Near the rear end of each plunger is a suitable vertically arranged slot 26^a adapted to receive a coin, the plunger being shallow enough to permit 125 the coin to extend upwardly in the path of lever 27^d. Above each slot, in the normal closed position of plunger 26, is the lower end of a tube or conduit 26^b, the upper end of the tube being secured to the housing 2, 130

the housing having suitable slots *a*, *b*, *c*, therein which open into the upper ends of the tubes 26^b, and through one of which slots the desired coin is inserted. The three slots 5 and also the tubes 26^b are of different sizes, according to the size of the coin intended to be used for controlling the operation of the pump. In the drawing the slot *a*, having the numeral 25 on the exterior of the 10 casing above said slot, is intended to admit a 25 cent coin, slot *b* a 50 cent coin and slot *c* a silver dollar.

In the bottom of casing 40 are slots 40^a which lead into tubes 124 secured to said casing, the lower ends of the tubes terminating above suitable receptacles 30^a provided in the forward ends of main plungers 30, which plungers are U shaped at their forward ends and are slidable in frame 54 secured to housing 2. The forward end of each plunger 30 is open so that one of the cams 7 may bear against the face of a coin deposited in the receptacle 30^a and enable the cam to force the plunger rearwardly as 25 shaft 5 is rotated. The cams are arranged on the shaft so that one of them will be effective to reciprocate one of the plungers when a coin is deposited in it.

Slots 54^a are provided in frame 54 at suitable points such that when any one of the plungers has reached the end of its rearward stroke the slot 54^a will be in register with the open bottom of the receptacle 30^a, said receptacle being substantially two aligned 35 grooves in the vertical sides of the plunger, the bottom of the plunger or horizontal floor of the plunger being perforated between the grooves so that when a coin is inserted into the grooves the lower edge of the coin will 40 rest on the upper surface of the frame 54 and as the plunger is moved on the frame the coin will be brought into register with slot 54^a in frame 54 whereupon the coin will drop through said slot and through tube 35 45 which is connected to frame 54, into box 37, which box is secured to the inner face of door 100, which door is hinged to the front side of housing 3 and opens outwardly.

Above each plunger 30 is a lever 41 which 50 is mounted on shaft 73, the shaft being revolubly mounted in housing 2. Each plunger is provided on its upper surface with a projecting lug 42 which as the plunger moves rearwardly strikes the lower end 55 of the lever and rocks the upper end forwardly. Another lever 41^a is secured to shaft 73 and is connected by rod 41^b to pawl 117 and the said movement of the lever insures the connection of pawl 117 and catch 9^a on pawl 9. When plunger 30 retracts as 60 hereafter explained lug 42, strikes lever 41 and rocks it forwardly, which in turn rocks lever 41^a rearwardly. This movement of the lever disconnects pawl 117 from catch 9^a 65 and the catch is free to drop into contact

with rack 6 and lock the shaft 5. The forward or retracting movement of any plunger 30 causes its finger 57 to strike and rock lever 56 whereby yoke 55 disconnects the clutch jaws and consequently shaft 18 is disconnected from gear 13.

Cable 22, which is adapted to be wound upon drum 20, is secured at its lower end to a weighted frame 69. Three stop bars 67 are loosely mounted in frame 69 and extend upwardly through apertures in frame 54. The upper ends of the bars are arranged close to the plunger bars 30 respectively and are bent to overlap the plungers. The extremity of each bar is turned downwardly and bears 80 on the upper surface of the adjacent plunger. Each plunger has a recess 74 in its top surface, which when the plunger is moved rearwardly will pass beneath the extremity of the corresponding rod 67, which 85 extremity will drop into the recess and prevent spring 31 which encircles plunger 30 from causing the plunger to retract. Spring 31 bears at one end against an overlapping portion 54^b on frame 54 and its other end 90 against a collar 30^b on plunger 30.

Rods 67 are each suitably graduated to indicate prices or quantities of the liquid to be vended and stops 68 are adjustably mounted thereon. The stops will be arranged on the rods at the proper points according to the coins which the device is adapted to receive at slots *a*, *b* and *c*. In Figs. 1 and 5 the lowermost stop is arranged at the 25 cent mark, the intermediate stop 95 at the 50 cent mark and the upper stop at the \$1.00 mark. When the pump is in operation the frame 69 is elevated by the winding cable 22. If a 25 cent coin has been inserted and its corresponding plunger 30 100 has been reciprocated until the rod 67 carrying the stop arranged at the 25 cent mark has engaged the recess 74 in said plunger, the frame 69 will rise on rods 67 and when it meets the stop 68 it will elevate the rod 105 and disconnect it from the plunger and permit spring 31 to cause the plunger 30 to retract and throw out the clutch on shaft 18 and stop the pump immediately. If either 110 of the other two plungers 30 are reciprocated by the insertion of the proper coin the rod 67 associated with the same will be the only one to engage it, the others being free, and the ascending weight 69 will, as it 115 meets the stops on the other rod or rods 67, merely elevate the rod or rods without releasing the rod connected to the particular plunger until the weight strikes its stop.

A suitable opening 28^a is provided in the 120 front of housing 2 at a suitable point, a glass plate being inserted in the housing to cover the same. Above this opening and on the inside of housing 2 is mounted a suitable spool 28 over which travels a ribbon 36, which ribbon passes through a cleat 125 125

fixed to the housing in the rear of opening 28^a. A weight 52 is connected to one end of the ribbon and a cord or wire 95 is connected to the other end of the ribbon. This 5 cord or wire 95 passes through a pipe 94 which is connected to storage tank 111 by gland 108 which gland is engaged in plate 110^a secured about a suitable opening in the tank. At the lower end of the rod 95 is 10 fixed a float 109. The ribbon is provided with graduations indicating the quantity of fuel in the tank. As the float descends the ribbon is drawn with it, the indicating graduations being visible through the aperture 15 in the housing. A suitable adjustable block 93 is provided in cord or rod 95 to permit of adjustment of the ribbon to varying sizes of storage tanks.

A lug 115 is secured at a suitable point 20 on cord or rod 95, and beneath it, at the proper point, is arranged the forked end of a rod 104 which rod extends upwardly and is connected by adjustable connection 114 to a cord or rod 99. The upper end of this 25 cord or rod 99 is connected by cords or rods 98 to opposite ends of plate 96 which is supported by spring 97 to a suitable part of the housing and in the rear of slots *a*, *b*, *c*. The plate is provided with downwardly 30 projecting extensions which are adapted to pass through suitable slots in the top of tubes 26^b or the devices connecting said tubes to housing 2. When stop 115 strikes the forked end of rod 104 it forces downwardly 35 said rod and its connections to plate 96 causing the projections on the plate to pass behind the slots *a*, *b*, *c* and close them. The forked end of rod 104 will be so positioned that the stop 115 will meet it when 40 the tank is substantially empty or contains an insufficient quantity of liquid to meet the value of the largest coin which the device is adapted to make use of.

The filter (Fig. 8) consists of casing 84, 45 to the upper portion of which suction pipe 38 is connected. The stop 83 is detachable and is held in place by thumb nuts 81 carried by lugs 82 which lugs are in swivel connection with case 84. A ring 85 removably fits within the top of case 84 and between the ring and the curved bottom of the case is a nest of suitably spaced screens 86, the cover or top 83 bearing down on the ring to hold the screens in place. The mesh 50 of each screen is preferably different from each of the others; that is, the lowest screen has a relatively coarse mesh, the one above it a finer mesh, the one above that still finer mesh and so on, the top screen having the 55 finest mesh of all the others. The screens serve to take out dirt and water and other objectionable matter which may be drawn up from the tank along with the fuel or other liquid to be pumped. The bottom of 60 case 84 is provided with an annular dis-

charge sleeve 87^a which carries at its upper end a deflecting hood 87. The lower end of sleeve 87^a is connected by nipple 89 to suction pipe 92, coupling 90 serving to connect the pipe to the nipple. Pipe 92 extends 70 through the open bottom of housing 3, the housing being anchored to a suitable foundation by bolts 91. As the liquid in the tank 111 is drawn through sleeve 87^a it discharges against hood 87 by which it is deflected downwardly and outwardly. The deflector will serve to separate some of the foreign matter since it retards the flow of the liquid and gives the foreign matter an opportunity of settling. The screens, however, do catch the foreign matter and water and the same fall into the bottom of the case where it may be withdrawn through bib cock 88. 75

The operation is readily understood. In 85 the normal inoperative position of the device unlocking plungers 26 are in their inner positions, main plungers 30 are in their forward positions, shaft 5 is locked by pawl 9, shaft 18 is disconnected from gear 13 and 90 hose drum 50 is locked by pin 120, the hose being wound up on the drum. The user will insert the coin he desires in the proper aperture *a*, *b*, or *c*—as, for example, aperture *b*. The coin passes down through the tube 26^b, 95 which leads from the aperture *b*, into the middle plunger 26, where it is held in a vertical position and transversely of the plunger. The user then pulls outwardly on said plunger until the coin drops out of the plunger through tube 124 into the middle main plunger 30, in which plunger the coin is held similarly to the position in which plunger 26 held it. As plunger 26 is withdrawn 100 the coin meets lever 27^a, rocking the same 105 and the connected shaft 118 and also levers 27^a and 27^b. The movement of the latter two levers unlocks the hose drum and the shaft 5 and the user draws out the hose and inserts the nozzle into the receptacle in 110 which he desires to place the liquid contained in the storage tank. He then rotates crank 63 and shaft 5 continuously in one direction. Cams 7 also rotate with the shaft, each one passing within the open end of the 115 plunger 30 in its rear. The coin having in the present illustration dropped into the middle plunger, the corresponding cam 7 makes contact with the coin and drives this plunger rearwardly. As the plunger moves 120 rearwardly its finger 57 meets lever 56 which, by means of yoke 55, throws in the clutch and connects shaft 18 to gear 13, which gear began to rotate as soon as shaft 5 began to revolve. The plunger continues 125 its rearward movement until the coin drops through tube 35 into box 37. At this instant the upper end of the middle stop bar 67 drops into recess 74 in the plunger and locks the same from retracting under the influence 130

of spring 31. The throwing in of the clutch connects gears 15 and 16 and cable drum 20 begins to wind up cable 22 and to elevate weight frame 69. Crank disk 24 is also rotated and the plunger is reciprocated in the pump cylinder to force the liquid in the storage tank through the filter, cylinder, hose and nozzle into the user's receptacle. The liquid continues to flow so long as the user rotates shaft 5 and until the ascending weight frame meets the stop on the middle bar 67, which bar has locked the middle main plunger. During the ascent of frame 69 it met the stop set for the lesser quantity of liquid—the 25 cent quantity in the present illustration, and elevated the stop bar to which it is connected, but, since said bar was not connected to its corresponding main plunger 30, said plunger not having been moved by the rotation of its corresponding cam, the middle plunger which was moved is not affected by the elevation of said bar. When the weight frame 69 meets the stop on the middle bar it elevates the same, thereby disconnecting it from the middle plunger and the spring on said plunger instantly drives the plunger forwardly to its normal position. Finger 57 on the plunger again meets lever 56 as the plunger moves forwardly, which lever, through yoke 55, throws out the clutch and shaft 18 is disconnected from gear 13, and gears 15 and 16 are separated. The pump thereupon ceases to work, the cable drum ceases its winding rotation and the weight frame 69 falls by gravity to its lowermost position, the cable necessarily unwinding with it. As soon as lug 42 meets lever 41 the latter is rocked to disconnect pawl 117 from its engagement with latch 9 on pawl 9, which pawl 9 drops into connection with rack 6 on shaft 5 to lock the same from further rotation until another coin is inserted. The pawl 9 and its connection to lever 27^a are of sufficient weight to rotate, as they descend, shaft 118 in the reverse direction. This movement of shaft 118 carries with it lever 27^a which throws in pin 120 so that when the hose is permitted to be wound up on drum 50 by spring 25 the pin will engage the lug 50^a on said drum and lock the drum from rotation in the unwinding direction, and until the pin is again released. Plunger 26 is forced back within the housing at any time after the pump ceases to operate.

The quantity of liquid in the tank will be indicated by the ribbon 36 and if the tank is empty the apertures *a*, *b*, *c* will be closed by plate 96.

It will be apparent that the coin apertures, tubes, the plungers, cams and lock bars may be multiplied as desired. I do not intend to limit the control of the operating mechanism by any one of three coins, but contemplate providing any desirable num-

ber of coin controlling mechanisms. There must be provided a complete unlocking mechanism for each coin by which the apparatus is intended to be controlled. The coins need not be money, but may be formed of any suitable material, especially where the apparatus is set up at a place of business where a consumer could purchase of the owner disks suitable for the purpose. The money will be the most convenient, however, since the apparatus may be installed along country highways, as well as on city streets, where coins will generally be the most convenient for the consumer.

What I claim is:

1. The combination, with a pump mechanism, of a shaft for actuating the pump mechanism, a driving shaft, means for connecting the two shafts, a coin-controlled reciprocable plunger for operating the said means, and means to lock the plunger at the end of one of its strokes consisting of a bar slidably engaging upon the plunger, the plunger having a recess to receive the bar when the same are in register, an adjustable stop on the bar, and a movable member having a releasable and operative connection to one of the shafts and adapted to abut the stop for releasing the bar from the plunger.

2. The combination with a pump mechanism, of a crank shaft for reciprocating the pump mechanism, a driving shaft adapted to be connected to the crank shaft, a plunger having a coin-controlled connection to the driving shaft and adapted to be reciprocated in one direction thereby when a coin is inserted in the plunger for causing the two shafts to be connected, means to lock the plunger at the end of its said stroke said means carrying an adjustable stop, a movable member having a releasable connection to one of the shafts and adapted to abut the stop for releasing the plunger, and means to retract the released plunger for disconnecting the two shafts.

3. The combination with a pump mechanism of a crank shaft for operating the pump mechanism, a driving shaft, a clutch mechanism for connecting the two shafts, a reciprocable plunger for actuating the clutch mechanism, the plunger having a coin-controlled connection to the driving shaft, for reciprocation thereby locking means to lock the plunger at the end of one of its strokes, means to release the locked plunger after a predetermined number of revolutions of one of the shafts, comprising an adjustable stop carried by the locking means and a movable member adapted to abut the stop and having a releasable connection to the last named shaft, and means to retract the released plunger.

4. The combination with a pump mechanism of a crank shaft for reciprocating the

- pump mechanism, a driving shaft, means for connecting the two shafts, a pawl for locking the driving shaft, a hose drum, a pin for locking the drum, a series of levers connected respectively to the locking pawl and pin, a coin-controlled plunger adapted to operate the levers for releasing the said pawl and pin, and a reciprocable plunger having a coin-controlled connection to the driving shaft and adapted to be operated thereby and adapted as it is reciprocated to actuate the first named means for connecting and disconnecting the crank shaft and the driving shaft.
5. The combination, with a pump mechanism, of a crank shaft connected to the pump mechanism, a driving shaft, a clutch for operatively connecting the two shafts, means to lock the driving shaft from unauthorized rotation, coin controlled means having a connection to the locking means for releasing the same, a coin controlled reciprocable plunger adjacent the driving shaft and actuated thereby and having an operating connection to the clutch for connecting the two shafts, a stop bar for engaging the plunger at the end of its clutch actuating stroke and having thereon an adjustable stop, a member having an actuating connection 20 with one of the shafts and in slidable engagement with the stop bar and adapted to abut the said stop after a predetermined number of revolutions of said shaft, and release the bar from the plunger, and means 25 to reciprocate the plunger in the opposite direction for actuating the clutch to disconnect the two shafts.
6. The combination with a pump mechanism of a crank shaft connected to the pump mechanism for operating it, a driving shaft, a clutch mechanism for connecting said two shafts, a plurality of reciprocable plungers adjacent the driving shaft, means in each plunger for retaining a coin, means on the 30 driving shaft adapted to reciprocate any plunger in one direction when a coin is inserted therein, means to reciprocate each plunger in the opposite direction, means to deliver coins of different sizes to the 35 plungers respectively, means on each plunger to actuate the clutch mechanism for connecting or disconnecting the two shafts as the plunger is reciprocated in either direction, a stop bar for each plunger 40 adapted to lock the same at the end of one of the strokes, an adjustable stop on each bar, and means operatively connected to one of the shafts for engaging any or all of the stops and releasing the locked plunger, the 45 latter thereupon being permitted to reciprocate in the opposite direction for disconnecting the two shafts and also the latter means from the shaft by which it is operated.
7. The combination with a pump mechanism and storage tank having a connection 50 to the suction side of the mechanism, of a hose winding drum and hose connected to the discharge side of the mechanism, a pin to lock the winding drum from unauthorized rotation when the hose is wound thereon, a crank shaft connected to the pump mechanism, a driving shaft, a clutch mechanism for connecting the two shafts, a reciprocable plunger having a coin controlled connection to the driving shaft whereby it 55 is reciprocated in one direction by the said shaft, means to deliver a coin to said plunger, means to lock the plunger at the end of said reciprocation, means to reciprocate the plunger in the opposite direction, means 60 to release the said locking means having an operative connection to one of the shafts, means to lock the driving shaft, rocking levers in connection with the latter locking means and with the hose locking pin and a reciprocable plunger having a coin controlled connection to the rocking levers for 65 actuating the same.
8. The combination with a pump mechanism, a plurality of shafts for operating the mechanism, a clutch mechanism for connecting and disconnecting the shafts, a pivotally mounted pawl, a rack secured to one of the shafts and adapted to be engaged by the pawl for locking the said shaft, a hose drum 70 and hose having a connection to the discharge side of the pump mechanism, a pivotally mounted pin for engaging the drum to prevent unauthorized withdrawal of the hose, a revoluble shaft having thereon a plurality of levers, one of which is connected to the pawl and another to the said pin, a plunger reciprocable adjacent said latter shaft and having means thereon for retaining a coin which coin, when the plunger is 75 reciprocated in one direction, abuts another of said levers on said latter shaft and actuates the same to release the pawl and pin, means to retain the pawl in its released position and means to disconnect the latter 80 means from the pawl to permit it to engage the said rack after a predetermined number of revolutions of the shaft.
9. The combination with a housing, of a pump mechanism within the housing, a revoluble hose drum and hose having a connection to the pump mechanism, a pivotally mounted pin for locking the drum, a crank shaft for operating the pump, a driving shaft, a clutch mechanism for connecting 85 and disconnecting the two shafts, means to lock the driving shaft, a plurality of coin apertures in the housing, a plurality of conduits connected to the housing and adapted to convey coins of different sizes, a reciprocable plunger below the lower end of each conduit, each having means therein for retaining the coin delivered to it by the corresponding conduit, a series of levers adapted 90 to be actuated by the coin in any plunger as 95

- the plunger and coin are reciprocated in one direction, one of said levers being connected to the hose drum locking pin and another to the locking means for the driving shaft 5 and adapted when rocked to unlock the said drum and said shaft, a second series of coin conduits below said plungers and having their upper ends terminating immediately below the points to which the plungers carry 10 the coins when reciprocated, a plurality of reciprocable plungers adjacent the lower ends of the latter conduits respectively, each having means therein for retaining a coin delivered to it by the corresponding conduit 15 above it, means on the driving shaft for bearing on the coin and thereby reciprocating the plunger in one direction, means on the plunger for actuating the clutch mechanism to connect or disconnect the said two 20 shafts, a spring on each latter plunger for reciprocating it in the opposite direction, a bar for each said plunger adapted to engage it at the end of one of its strokes, an adjustable stop on each bar, a traveling frame in 25 slidable engagement with the bars and adapted to abut the said stops for elevating the said bars and releasing the locked plunger, said frame having a releasable connection to one of the shafts for elevating it, and 30 means below each of the latter plungers for receiving and discharging the coin carried by the plunger at the end of one of its strokes.
10. The combination with a pump mechanism of a crank shaft for reciprocating the pump mechanism, a driving shaft, means for connecting the two shafts, a pawl for locking the driving shaft, a hose drum, a 35 pin for locking the drum, a series of levers connected respectively to the locking pawl 40 and pin, a coin-controlled plunger adapted to operate the levers for releasing the said pawl and pin, a reciprocable plunger having a coin-controlled connection to the driving shaft and adapted to be operated thereby 45 and adapted as it is reciprocated to actuate the first named means for connecting and disconnecting the crank shaft and the driving shaft, means to lock the last named plunger at the end of one of its strokes and 50 means to release the locked plunger having a releasable connection to one of the shafts and adapted to be operated thereby.
11. The combination with a pump mechanism of a crank shaft for operating the 55 pump mechanism, a driving shaft, a clutch mechanism for connecting the shafts, a coin-controlled plunger for operating the clutch mechanism, means on the driving shaft to reciprocate the plunger in one direction 60 when a coin is inserted in the plunger, means to retract the plunger for operating the clutch mechanism to disconnect the two shafts, means to lock the plunger at the end 65 of its first named stroke said means comprising a locking member in contact with the plunger and carrying an adjustable stop and means having a releasable connection to one of the shafts and adapted to abut the stop for releasing the locking member. 70

In witness whereof, I hereunto subscribe my name this 7th day of February, 1914.

NATHANIEL D. HULL.
